UNITED STATES PATENT OFFICE

MARCEL OSWALD, OF NANTERRE, FRANCE, ASSIGNOR TO COMPAGNIE LORRAINE DE CHARBONS POUR L'ELECTRICITE, OF PARIS, FRANCE, A CORPORATION OF FRANCE

CARBON FOR ELECTROTECHNICAL USES AND PROCESS OF MANUFACTURE THEREOF

Application filed May 24, 1928, Serial No. 280,362, and in France April 8, 1927.

This invention relates to improved carbons and the like adapted for electro-technical uses and to a process of manufacture thereof.

These improved carbons, which are inexpensive and which can be used with perfect safety, are adapted to serve as substitutes for carbons to be connected electrically with a metal in all cases where the connection is usually effected by setting the carbon in a metallic mount, by surface metallization or otherwise, with greater ease of attachment and certainty of intimate contact at the points of connection. With the use of these carbons it is possible to dispense with the employment of separate metallic elements to be connected to the carbon, there being substituted therefor a simple metallic covering or coating applied in manner hereinafter described.

20 The process of manufacturing the improved carbons consists primarily in producing roughness or rugosity over all or part of the surface of the carbon to be metallized by rupture, after hardening, of a carbon rod or 25 the like, at one or more places where the rod or the like has been weakened, as by notching it, while still soft.

By way of example there is described below with reference to the accompanying 30 drawing the simple case of the preparation of cylindrical carbon pads.

Fig. 1 is a perspective view partly cross-hatched showing a rod of carbon which has been freshly moulded, and not yet notched.

35 Fig. 2 is a like view showing the carbon rod notched or scored transversely.

Fig. 3 is a perspective view of a piece of the carbon rod after hardening and after 40 rupture.

45 Fig. 4 is a section on the line IV—IV of Fig. 3.

The soft carbon rod *a* resulting from a moulding operation or after passage through 45 a draw plate (Fig. 1) is notched circularly at *b'*, *b²*, *b³*, *b⁴*, *b⁵*, to a depth which constitutes a small fraction of its diameter (Fig. 2). The notches *b* are cut in parallel planes and at distances apart such that two consecutive notches *bⁿ⁻¹*, *bⁿ* are so spaced that the

intermediate body is about equal in volume to that of a finished carbon element *A*.

The long carbon rod thus notched having been allowed to harden, rupture is effected by application of a relatively slight effort 55 at the notched points *b'*, *b²*, *b³*, *b⁴*, *b⁵*.

It is known that after hardening the carbon is of the same geometrical form as in the raw state and that with but slight shrinking it is of substantially the same dimensions. 60

The rupture results in the formation of carbon elements *A* having end faces *B* each including a smooth annular region *c* at the part where the notch was made in the carbon rod when soft, and a central rugose or rough 65 surface *d* particularly adapted to receive a metallic coating.

It is evident that the process described is applicable, mutatis mutandis, what ever be the form of the carbon element and that it 70 may be applied to materials other than carbon in which case it suffices to cut in the carbon or like body after moulding, and while in a soft state, notches, scores, or incisions which facilitate rupture after hardening, leaving at 75 the faces where the rupture is made one or several central rough regions each bounded by a narrow smooth region where the notch or the like was formed.

These rough parts are then covered with 80 an adherent metallic covering by the aid of any known process such as electrolysis, abrasion, pulverization, chemical precipitation, cathodic bombardment and so on.

In utilizing the electrolytic process for 85 example it suffices to connect the carbon to the cathode in an electrolytic bath to deposit on the carbon metal from the bath. If abrasion is resorted to, the rough carbon surface is rubbed vigorously on a mass of the 90 metal which is to be fixed to the carbon. Pulverization is preferably effected by a spraying process employing a pistol. Chemical precipitation may be effected in manner similar to that adopted for chemical silvering. Cathodic bombardment is referred to 95 as an alternative which is hardly sufficiently economical to be utilized in practice.

The advantages of the new process reside 100 in the simplicity and ease of manufacture.

on a large scale and also in the economy which results from dispensing with the moulding of separate sections of carbon, and from the replacement by a cheap metallic 5 coating or covering which can be easily and readily effected of the special and expensive metallic pieces such as caps, straps, terminals, plates etc. heretofore used.

Among the possible applications of the 10 invention there may be mentioned by way of example:—

1. The mounting of anodes for batteries. In the use of the improved carbons it is unnecessary to observe strict tolerances with 15 regard to diametral dimensions of the anodes.
2. The mounting of cylindrical brushes with copperized heads for magnetos or small universal motors.
3. The connection of the rods of carbon or carborundum as resistance electrodes of arc or electrical furnaces.

The invention also lends itself to the employment of complex metallic coverings 20 comprising different metals juxtaposed or superposed. In this case the several metal coatings are applied successively to the parts of the carbon which are to receive the metal.

The rough parts obtained in the manner 25 described are also adapted to receive non-metallic coverings which may or may not be colloidal, for example, such as employed in the battery and accumulator industry. In the application of such coverings it is preferable to use the pulverization process 30 which projects a solution in the form of fine drops by means of a compressed air or gas jet.

What I claim is:—

- 40 The method of making carbon conductors metallized on the end, comprising, grooving circumferentially a carbon rod while soft, at length intervals equal to the desired lengths of the conductors, breaking the rod 45 in the planes of the grooves providing the conductors thus separated, with rough end surfaces of fracture, bounded by the smoother walls of the said grooves, and metallizing the said surfaces of fracture.
- 50 In testimony whereof, I have affixed my signature.

MARCEL OSWALD.
